MILK CRATE

**Jesus Luis Garcia Chavez, Privada Narciso Mendoza 97,
Ote. Torreon, Coahuila, Mexico**

Filed Aug. 18, 1972, Ser. No. 281,776

Term of patent 14 years

Int. Cl. D9—03

U.S. Cl. D9—177

FIG. 1

FIG. 2

FIG. 3

FIG. 4

FIG. 1 is a side-elevational view of a milk crate showing my new design;

FIG. 2 is a bottom plan view thereof;

FIG. 3 is a top plan view; and

FIG. 4 is an end view of the milk crate.

The side and end not shown are the same in appearance as the respective side and end shown.

I claim:

The ornamental design for a milk crate, substantially as shown and described.
